UNITED STATES PATENT OFFICE.

STERLING ELLIOTT, OF NEWTON, MASSACHUSETTS.

MACHINE FOR IMPRESSING CHARACTERS ON STENCIL-BLANKS.

1,378,771.

Specification of Letters Patent.

Patented May 17, 1921.

Application filed October 27, 1916. Serial No. 128,122.

To all whom it may concern:

Be it known that I, STERLING ELLIOTT, a citizen of the United States, residing at Newton, in the county of Middlesex and

5 State of Massachusetts, have invented an Improvement in Machines for Impressing Characters on Stencil-Blanks, of which the following is a specification.

Many stencils adapted for use with addressing machines have the addresses impressed upon them by means of a typewriting machine, or machine having the characteristics of a typewriting machine. When impressing an address, the stencil-blank is 10 arranged on or wrapped about the cylinder of the typewriting machine, and consequently is bent into circular form, and such bending of the blank is objectionable for the reason that the usual addressing machines require the stencils to be arranged 15 in flat form, and when they have been once bent and the fibrous structure of the paper consequently distorted, it is very difficult to restore them to flat form.

20 This invention has for one of its objects the provision of holding-means adapted to be applied to a typewriting machine and adapted to hold a stencil in flat form, in tangential relation to the surface of the cylinder of the typewriting machine, for correct engagement therewith by the usual type keys preferably in front of the cylinder; said holder being connected with the usual carriage of the typewriting machine 25 and adapted to be moved along with it, step by step, as the type-keys are operated.

Another object of the invention is the provision of line-spacing means associated with the holding-means for the stencil-blank, by which the stencil-blank may be moved to different elevations to present different portions thereof to the type-keys for the different lines.

Another object of the invention is the provision of means for automatically restoring the line-spacing means to normal position when the holding means is operated to disengage the stencil-blank, so that each time a stencil-blank is placed in engagement with 50 the holding-means the line-spacing means

will be in correct position to begin the type-impressing operation.

Another object of the invention is the provision of means for depositing carbon on the back of the stencil-blank in areas corresponding to the areas of the type, so that impressions on the stencil-blank will be 55 visible.

Figure 1 is a vertical section of the portion of a typewriting machine having holding-means for a stencil-blank embodying 60 this invention.

Fig. 2 is a side elevation of the holding-means.

Fig. 3 is an enlarged or full-sized front 65 elevation of the holding-means.

Figs. 4, 5 and 6 are fragmentary details of the holding-means to be referred to.

Referring to Fig. 1, wherein a portion of a typewriting machine of ordinary construction is shown, 10 represents the machine-frame, 11 one of the pivoted type-bars adapted for movement toward and from the cylinder 12, and 13 is a type-key for operating the type-bar 11. The machine 70 herein represented is adapted for visible writing, but it is obvious that other forms of typewriting machines may be employed.

15 represents the stencil-blank of ordinary construction upon which characters, which 80 may form an address, are adapted to be impressed by the type. In Figs. 1 and 4, said blank 15 is adapted to be held in flat form, and in tangential relation to the surface of a cylinder 12, and, as here shown, in front 85 of said cylinder so that when struck by the type the impressed address will be visible. Said blank is held by a suitable holding-means borne by the carriage 24, and is movable with said carriage, and comprises a 90 clamping device adapted to engage the blank and line-spacing means associated therewith. As here shown, said clamping-device comprises a pair of stationary jaw-members 18, for engaging the rear side of 95 the end-portion of the blank having lateral extensions 19, with forwardly extended ears 20, which engage the edges of the blank, at opposite ends thereof, and locate the blank with respect to the clamping- 100

device. Said stationary jaw-members are formed or provided at the extremities of a pair of frame-bars 21, which are pivoted at 22, to projections 23 extended rearward 5 from the typewriter carriage 24. These frame-bars are rigidly secured together by the pivot-rod 22, and by a rod 25, and also by other means, as will be hereinafter described, thus to form a rigid structure, 10 which, as an entirety, is adapted for movement about a horizontal axis on the pivot-rod 22. Said clamping-device also comprises a pair of front jaw-members 26, pivoted at 27, to the frame-bars 21, and 15 adapted to be held pressed into engagement with the rear jaw-members or with a stencil-blank which may be disposed between them, by flat springs 28 attached to the frame-bars at one end, the opposite or 20 free ends of which bars bear upon the front jaw-members, thus the stencil-blank is adapted to be held normally by the spring-pressed jaw-members. As here shown, said jaw-members are arranged above and at the 25 front of the cylinder 12, so as to hold the stencil-blank in a vertical position in front of the cylinder, and in tangential relation to the surface thereof for visible impression of the type, as represented in Fig. 4.

30 The front jaw-members are adapted to be moved outwardly by means adapted for manual operation, and, as here shown, said operating means consists of a yoke 30, see Fig. 3, arranged between the frame-bars 21, 35 and loosely mounted on the rod 27, having the extremities of its short arms extended laterally, as at 31, to form projections which extend beneath or in rear of the movable front jaw-members 26, for engagement with 40 said members, to move them outwardly and disengage the stencil-blank. Said yoke has arranged on it, intermediate its length, an arm 32, and said arm is disposed in front of an arm 33, fixed to a cross-bar 34, arranged 45 between the frame-bars 21, so that the two arms may be grasped by the fingers and thumb, and pressure exerted upon the front arm 32, thereby to rock the yoke and move the front jaw-members to disengage the 50 stencil-blank. Said operating-means, as here shown, is adapted to be restored to normal position by gravity.

The stencil-blank while held by the clamping-device will be moved vertically, step by step, for spacing the several lines of an address, and for this purpose a line-spacing means is provided which, as shown, is adapted for manual operation. The line-spacing means may comprise a roll 35, see Figs. 4 55 and 6, journaled in an ear 36, fixed to a hub 37, secured to a rod 38, which is secured at its ends to the end-portions 39, of a yoke 40, which is in turn secured to upright ears, on 60 the carriage 24. Said roll 35 is thus movable 65 bodily with the carriage, and is freely rota-

table and serves as a roller support, and receives upon it a cam 41, which is supported by the pivoted frame-bars, and thus supports said frame-bars and parts borne by them in an elevated position. Said cam 70 is made of a varying radius, so that as it is turned the frame-bars and clamping-device supported thereby will be raised to and held at different elevations, to correspondingly vary the elevation of and hold the stencil- 75 blank.

The cam 41 is secured to a shaft 42, see Fig. 5, having its bearings in the frame-bars 21, and said shaft has secured to it at one end a knurled head adapted to be engaged and turned by the fingers, when desired, to rotate the cam and lift the clamping-device. The cam 41 normally rests against a fixed pin 51, on the frame-bar, in which position that portion thereof of shortest radius will engage the roll 35, and when it is desired to move the stencil-blank bodily in an upward direction, to present another portion thereof to the type, the shaft 42 will be turned to correspondingly rotate the cam. 80 A spring 57 is arranged about the shaft 42, and connected at one end therewith and at the other end to the frame-bar, which acts to hold the cam 41 against the fixed pin 51, or to turn the shaft 42 backward until the 85 cam reengages said fixed pin 51, in case it has been rotated forwardly to correspondingly turn the cam.

Means are associated with said shaft 42, by which it is adapted to be held against 100 backward rotation and also in several different elevated positions to predetermine the position of the lines. Said means, as here shown, consists of a wheel 43, adapted for connection with the shaft 42, having ratchet 105 teeth on its periphery adapted to be engaged by a detent 44, on an arm 45, which is loosely pivoted at 46, to one of the frame-bars 21. Said detent arm has a limited movement only on its pivot by reason of the 110 slotted end-portion 47, see Fig. 2, engaging a pin 48, on the frame-bar. The detent acts to hold the ratchet-toothed wheel in any position it may be set, by the rotation of the shaft 42, but permits turning movement in 115 one direction only.

The teeth on said wheel are arranged in groups, here shown as three in number, and each group has a different number of teeth, as for instance, one group may have three 120 teeth, another group four teeth, and another five teeth, and each group of teeth includes approximately the same arc or portion of the wheel, so that the teeth of the several groups may vary in length. This provides 125 for varying the number of lines and also for spacing the lines more or less widely apart.

The last tooth of each group is made higher than the remaining teeth of the group, see Fig. 4, and said high teeth serve 130

as stops to check further rotation of the ratchet-wheel by a turning movement of the shaft 42, and the limited movement of the detent-arm is such that the detent may be 5 raised high enough to pass over the several teeth of the group with the exception of the last high tooth, but will not be raised high enough to pass over said last tooth, so that further advancing movement of the ratchet 10 wheel is prevented. Said wheel, however, is adapted to be reset automatically by means to be hereinafter described. Said wheel is also adapted to be moved or adjusted relatively to the shaft to bring its different 15 groups of teeth into co-operative relation with the detent, and, as here shown, it is mounted to slide longitudinally on the shaft for a short distance, and is connected therewith by a spring 49, which latter acts to 20 draw it onto the shaft against the cam 41, or other abutment, and it is adapted to be held from rotation on the shaft by a pin 50, projecting from the cam or other abutment, which enters one or another hole in the hub 25 of the toothed wheel. There are as many holes provided as there are groups of teeth on the wheel. By this structure, the wheel may be drawn outward by the fingers engaging a knurled head thereon, against the action 30 of the spring 49, far enough to disengage the pin 50, whereupon it may be turned to bring any other hole into position to receive said pin, and consequently any of the several 35 groups of teeth into position for engagement with the detent. When set in any position, it will be turned with the shaft. The ratchet-wheel 43, having been moved to bring any of its groups of teeth into position 40 for co-operation with the detent, it will be held with the cam 41 in engagement with the pin 51, by the spring 57, and the detent will engage the first tooth of the group. The first line of the address may then be impressed on the stencil-blank by the type. 45 Then the shaft 42 will be turned a distance corresponding to one of the teeth of the wheel 43, whereupon the detent will pass over the first tooth and will engage the second tooth and the cam will be correspondingly moved to lift the clamping-device bearing the stencil-blank into position for the next line. This operation may be 50 repeated for the different lines, or until the full number of teeth of the group have been successively brought into detent-engaging position, whereupon the high tooth at the end of the group of teeth will be brought into detent-engaging position, over which 55 said detent cannot pass, whereupon the intermittent movement of the line-spacing means ceases.

After the stencil has been impressed by the type and it is desired to remove it from the clamping-device, the clamping device is operated to accomplish this result, as above

set forth, and at such time the line-spacing means is also adapted to be operated automatically and is caused to resume its normal position. For the accomplishment of this result, suitable connecting means are provided between the detent-arm and the clamping-device by which said arm will be lifted and its detent removed from engagement with the toothed wheel by a movement of the clamping-device. 70

Referring to Fig. 4, the detent-arm 45 has connected with it one end of a link 55, the other end of which is loosely connected with an ear 56, on one of the movable jaw-members, so that upon movement of said member, the detent-arm will be correspondingly moved and the toothed wheel disengaged. The toothed-wheel, cam, and cam-shaft 42 are then free to be rotated by the spring 57 to normal position, the cam engaging the 85 pin 51, and the first tooth of the group of teeth engaging the detent 44. 75

It is herein designed to deposit carbon on the back of the stencil-blank, in areas corresponding to the areas of the type, so that the type impressions may be visible at the front of the stencil-blank, and herein a strip of carbon-paper 60 is provided which is arranged in roll form in a hollow cylinder 61, and is adapted to be drawn from the roll over a guide 62, and then around the cylinder 12, and then over the top of the hollow cylinder 61, and for the purpose of holding said carbon-strip on the cylinder 12, a roll 65, see Fig. 6, may be employed, 100 which is loosely mounted on a rod 66, supported at its ends in bearing-strips 67, which are extended from a sleeve 68, mounted for convenience on the rod 38, and said roll is held pressed against the cylinder 12, 105 or carbon-paper thereon, by a spring 69. Said bearing-strips 67 may be extended at the other side of the sleeve and adapted to pivotally support an arm 70, which extends upward and has a weighted end-portion 110 overlying the hollow cylinder 61, which is employed to hold the used portion of the carbon-strip out of the way. 90

I claim:—

1. In a machine for impressing characters on stencil-blanks, the combination with the cylinder of a typewriting machine, a carriage, and a set of type, of holding-means borne by the carriage and vertically movably arranged adjacent and independent of the cylinder and adapted to engage and clamp a stencil-blank and hold it in flat form in tangential relation to the surface for the cylinder. 115

2. In a machine for impressing characters on stencil-blanks, the combination with the cylinder of a typewriting machine, a carriage, and a set of type, of holding means pivotally carried by the cylinder-supporting carriage disposed above and vertically mov- 120

- able independent of the cylinder and arranged to engage and clamp the edge of a stencil-blank and hold it in flat form, in front of and in tangential relation to the 5 surface of the cylinder.
3. In a machine for impressing characters on stencil-blanks, the combination with the cylinder of a typewriting machine, a carriage, and a set of type, of a clamping-device borne by and extended above the carriage arranged to engage and clamp the upper edge-portion of a stencil-blank, and means for supporting said clamping-device above the cylinder with the stencil-blank carried 10 by it arranged in tangential relation to the surface of the cylinder.
4. In a machine for impressing characters on stencil-blanks, the combination with the cylinder of a typewriting machine having 15 line spacing means, a carriage, and a set of type, of holding-means borne by the carriage and arranged adjacent the cylinder, and adapted to hold a stencil-blank in flat form in tangential relation to the surface of the cylinder, and separate line-spacing 20 means borne by the holding-means adapted for intermittent operation.
5. In a machine for impressing characters on stencil-blanks, the combination with the 25 cylinder of a typewriting machine, a carriage, and a set of type, of holding-means borne by the carriage and arranged adjacent the cylinder and adapted to hold a stencil-blank in flat form, in tangential relation to the surface of the cylinder, line-spacing 30 means independent of the cylinder arranged with said holding-means having rotatable actuating-means arranged for operation to raise the holding-means step-by-step, thus 35 to bodily lift the stencil-blank step by step.
6. In a machine for impressing characters on stencil-blanks, the combination with the cylinder of a typewriting machine, a carriage, and a set of type, of a clamping-device 40 borne by the carriage arranged to engage the upper edge-portion of a stencil-blank, and means for supporting said clamping-device adjacent the cylinder with the stencil-blank carried by it arranged in tangential relation to the surface of the cylinder, and line-spacing means independent of the cylinder borne by said clamping-device, adapted for moving said device bodily step by step.
7. In a machine for impressing characters on stencil-blanks, the combination with the cylinder of a typewriting machine, a carriage, and a set of type, of a clamping-device 45 borne by the carriage arranged to engage the upper edge-portion of a stencil-blank, and means for supporting said clamping-device adjacent the cylinder with the stencil-blank carried by it arranged in tangential relation to the surface of the cylinder, and line-spacing means arranged with
- said clamping-device, adapted for moving said device bodily step-by-step, and means connecting said line-spacing device with said clamping-device, whereby the former is adapted to be automatically restored to normal position subsequent to the completion of the impressed stencil. 70
8. In a machine for impressing characters on stencil-blanks, the combination with the cylinder of a typewriting machine, a carriage, and a set of type, of a pivotally supported clamping-device borne by the cylinder-supporting carriage, arranged to engage and clamp the upper edge-portion of a stencil-blank and hold the blank in flat form 75 in tangential relation to the surface of the cylinder. 80
9. In a machine for impressing characters on stencil-blanks, the combination with the cylinder of a typewriting machine, a carriage, and a set of type, of a pivotally supported clamping-device borne by the cylinder-supporting carriage, adapted to engage and clamp the upper edge-portion of a stencil-blank and hold the blank in flat form 85 in tangential relation to the surface of the cylinder, and line-spacing means independent of the cylinder and connected with said clamping-device for moving it intermittently in a vertical direction. 90
10. In a machine for impressing characters on stencil-blanks, the combination with the cylinder of a typewriting machine, a carriage, and a set of type, of a pivotally supported clamping-device borne by the carriage, arranged to engage the upper edge-portion of a stencil-blank and hold the blank in tangential relation to the surface of the cylinder, movable jaw members included in 100 said clamping device, and line-spacing means connected with said clamping-device for moving it intermittently in a vertical direction, said line-spacing means being automatically restored to normal by movement of the movable jaw-members of the clamp- 105 ing-device. 110
11. In a machine for impressing characters on stencil-blanks, the combination with the cylinder of a typewriting machine, a carriage, and a set of type, of a pivotally supported clamping-device borne by the carriage adapted to engage the edge-portion of a stencil-blank, and hold the blank in tangential relation to the surface of the cylinder, and line-spacing means carried by said 115 clamping-device for moving it intermittently in a vertical direction, and means connecting said line-spacing device with the movable jaw-members of the clamping-device, whereby the former is moved by the latter and permitted to resume its normal position. 120
12. In a machine for impressing characters on stencil-blanks, the combination with the cylinder of a typewriting machine, a 130

- carriage, and a set of type, of a movably supported clamping-device borne by the carriage, adapted to engage a stencil-blank, and hold the blank in flat form, in tangential relation to the surface of the cylinder, a bearing, and cam engaging the bearing for holding the clamping-device in a predetermined position, and means for rotating said cam to lift the clamping-device.
- 10 13. In a machine for impressing characters on stencil-blanks, the combination with the cylinder of a typewriting machine, a carriage, and a set of type, of a movably supported clamping-device borne by the carriage, adapted to engage a stencil-blank, and hold the blank in tangential relation to the surface of the cylinder, a bearing, a cam engaging the bearing for holding the clamping-device in a predetermined position,
- 15 means for rotating said cam to lift the clamping-device, a spring for restoring said cam to normal position, and means connecting said clamping-device with the actuating means for the cam, whereby the spring is permitted to act and restore the cam.
14. In a machine for impressing characters on stencil-blanks, the combination with the cylinder of a typewriting machine, a carriage, and a set of type, of a pivotally supported clamping-device borne by the carriage adapted to engage a stencil-blank and hold it in flat form in tangential relation to the surface of the cylinder, a cam associated with the clamping-device, a bearing on which said cam rests, means for rotating said cam to bodily lift the clamping-device and stencil-blank borne by it, a ratchet-wheel arranged on the cam-shaft, a detent therefor adapted to hold the cam in different predetermined positions, to hold the clamping-device in different elevated positions.
- 30 15. In a machine for impressing characters on stencil-blanks, the combination with the cylinder of a typewriting machine, a carriage, and a set of type, of a pivotally supported clamping-device borne by the carriage adapted to engage a stencil-blank and hold it in flat form in tangential relation to the surface of the cylinder, a cam associated with the clamping-device, a bearing on which said cam rests, means for rotating said cam to bodily lift the clamping-device and stencil-blank borne by it, a ratchet-wheel arranged on the cam-shaft, a detent therefor adapted to hold the cam in different elevated positions.
- 35 16. In a machine for impressing characters on stencil-blanks, the combination with the cylinder of a typewriting machine, a carriage, and a set of type, of a pivotally supported clamping-device borne by the carriage adapted to engage a stencil-blank and hold it in flat form in tangential relation to the surface of the cylinder, a cam associated with the clamping-device, a bearing on which said cam rests, means for rotating said cam to bodily lift the clamping-device and stencil-blank borne by it, a ratchet-wheel having a plurality of groups of ratchet-teeth, the teeth of each group varying in number, said wheel being adjustably arranged on the cam-shaft, and a detent therefor adapted to hold the cam in different elevated positions.
- 40 17. In a machine for impressing characters on stencil-blanks, the combination with the cylinder of a typewriting machine, a carriage, and a set of type, of a pivotally supported clamping-device borne by the carriage adapted to engage a stencil-blank and hold it in flat form in tangential relation to the surface of the cylinder, a cam associated with the clamping-device, a bearing on which said cam rests, means for rotating said cam to bodily lift the clamping-device and stencil-blank borne by it, a ratchet-wheel arranged on the cam-shaft, a detent therefor adapted to hold the cam in different elevated positions, to hold the clamping-device in different elevated positions, and means for disengaging the detent on the ratchet-wheel, a spring for returning the cam-shaft and parts connected therewith to normal position when the ratchet-wheel is disengaged.
- 45 18. In a machine for impressing characters on stencil-blanks, the combination with the cylinder of a typewriting machine, a carriage, and a set of type, of holding-means borne by the carriage and arranged adjacent the cylinder and adapted to hold a stencil-blank in flat form in tangential relation to the surface of the cylinder, a hollow cylinder adapted to contain the roll of carbon-paper in strip form, guiding-means for said strip, said carbon-strip being adapted to extend around the cylinder, and means to support and guide the free end-portion of said strip.
- 50 19. In a machine for impressing characters on stencil-blanks, in combination with blank-holding means, and a set of type, of line-spacing means associated with said holding means operable to advance the stencil-blank relative to the type including a ratchet-wheel having a plurality of groups of teeth, each group occupying a substantially equal extent of the periphery, certain of said groups having differing numbers of teeth, and a pawl to engage said teeth.
- 55 20. In a machine for impressing characters on stencil-blanks, in combination with blank-holding means, and a set of type, of

line-spacing means associated with said holding means operable to advance the stencil-blank relative to the type including a ratchet-wheel having a plurality of groups 5 of teeth, each group occupying a substantially equal extent of the periphery, certain of said groups having differing numbers of teeth, a pawl engageable with said teeth, means to adjust said spacing means for the 10 engagement of said pawl with a particular group of teeth of said ratchet wheel, and means to prevent engagement of said pawl with teeth of other groups on said wheel.

21. In a machine for impressing characters on stencil-blanks, in combination with blank-holding means, and a set of type, of pivotally-supported line spacing means associated with said holding means operable to advance the stencil-blank relative to the 15 type including an operating shaft, a ratchet-wheel rotatably carried thereby having a

plurality of groups of teeth, each group occupying a substantially equal extent of the periphery, certain of said groups having differing numbers of teeth, a pawl engageable with said teeth, said ratchet wheel formed with stops separating each group of teeth engageable with said pawl to restrict further movement of said wheel, and means to prevent the manual disengagement of 25 said wheel from said shaft for its independent rotation to present a different group of teeth to be engaged by said pawl, and its subsequent driving reengagement therewith in a relatively moved position. 30

In testimony whereof, I have signed my name to this specification in the presence of two subscribing witnesses.

STERLING ELLIOTT.
